UNITED STATES PATENT OFFICE.

LOUIS C. DIMMICK, OF LOUISVILLE, KENTUCKY, ASSIGNOR TO ABRAHAM KNOBEL, OF SAME PLACE.

DESIGN FOR AN AWNING-HOOK.

SPECIFICATION forming part of Design No. 34,222, dated March 12, 1901.

Application filed February 14, 1901. Serial No. 47,387. Term of patent 7 years.

To all whom it may concern:

Be it known that I, LOUIS C. DIMMICK, a citizen of the United States, residing at Louisville, in the county of Jefferson and State of Kentucky, have invented and produced a new and original Design for Awning-Hooks, of which the following is a specification, reference being had to the accompanying drawing, forming part thereof.

10 The figure is a plan view of an awning-hook, showing my new design.

The body of the hook is round, being made of round wire. The ends *a* and *b* are pointed.

15 At *c* the body of the shank *s* is deflected to the right about half its diameter.

At *d* the body of the hook makes a sharp turn to the left at a right angle to the shank *s*.

The top *e* is horizontal.

At *m* the body of the hook turns downward sharply.

The portion *h* is horizontal and slightly lower than the portion *e*.

At *i* the body of the hook makes a circular curve downward till the straight portion *j*, bearing the point *a*, is nearly or quite parallel with the shank *s*. The inner curves correspond to the outer, having a sharp upward-extending portion, (shown at *k*.)

Having thus described my invention, what I claim as new, and desire to secure by Letters Patent, is—

The design for an awning-hook as herein shown and described.

L. C. DIMMICK.
